UNITED STATES PATENT OFFICE.

THOMAS DAVID MANUEL, OF BELLVILLE, SOUTH AFRICA.

FUEL FILLER FOR TANKS.

Application filed March 26, 1926, Serial No. 97,722, and in the Union of South Africa December 10, 1925.

This invention is a filler for filling the fuel tanks of various types of motor vehicles having their petrol tanks at the rear or centre of the car, or fixed in any other 5 position in the vehicle, or for filling petrol tanks of any description with liquids from sealed packages.

One object of the present invention is the provision of means for filling the tanks 10 of motor vehicles with petrol in the minimum time and with the least trouble.

Another object of the invention is the construction of a gravity operating can puncturing funnel.

15 A further object of the invention is to provide an elevatable device of the class described which may be adjusted in height to suit the location of filler tanks.

Other objects of the invention will appear 20 as the description of the following preferred embodiment proceeds.

The invention is illustrated in the accompanying drawings in which:—

Fig. 1 is a side elevation of the filler. 25 Fig. 2 is a longitudinal section through the same, the support being omitted.

Fig. 3 is a cross section taken along the line 3—3 of Figure 2 viewed in the direction of the arrow.

30 Fig. 4 is a cross section taken in a plane adjacent the perforating device and

Fig. 5 is a side section of the perforating device.

Referring now in detail to the several 35 figures, the reference character (A) is a tripod stand in the centre of which is fixed firmly a hollow guide tube (B). (C) is a hollow tube arranged to telescope relative to the tube (B). At the top of the tube 40 (C) a support (P) is attached preferably having the shape of a pronged fork in which rests a triangular shaped chute (D) in an inclined position as shown. The lower end of the chute tapers into a funnel (D') 45 to the end of which funnel is connected a short length of hose pipe. The chute is secured to the fork in any suitable manner and the lower end of the fork fits inside the end of the hollow tube and is secured in that position by suitable means such as 50 a pin through the tube.

The tube (C) slides smoothly up and down in the tube (B) and may be fixed at any height necessary for any particular 55 vehicle or motor engine by means of the winged set screw (E). (F) is a triangular

metal strip or wear plate shaped as shown in Figures 3 and 5 fit flush inside of the chute (D). A gauze wire strainer (K) is fixed to the lower end of this strip projecting into the funnel of the chute and the strainer has the same taper as the inside of the funnel (D') which enables the strainer to fit tightly into such funnel. The metal strip (F) is removably fixed to the chute 65 by means such as screws.

(G) is a triangular shaped steel cutter fastened to the strip (F) by two bolts and nuts as shown in Figure 5, being detachable for sharpening when necessary. (H) is 70 a small cross bar firmly attached to the under side of the cutter (G) for the purpose of doubling back the lip of the petrol tin cut by the cutter (G) to enable the petrol to flow out freely.

75 (I) is a striking bar apparatus for the purpose of piercing a vent hole in the tin consisting of a bar (I') in the top end of which is fixed a sharp pin (M). Below the latter is a short piece of stiff clock-spring riveted to the bar as shown in Figure 6 for withdrawing the pin (M) away from the vent-hole after the hole has been made.

To the lower end of the striking bar is 80 fixed a spring (J), the other end of said spring being fixed within the upper end of the chute (D). The striker bar pivots round a circular rod (L) passing through the striker rod as shown in Figures 6 and 7.

The manner in which the invention is 85 performed is as follows:—

The apparatus is placed next the curb or in any desired position giving access to the tank to be filled and the hose pipe is inserted into the fuel tank, the triangular chute 90 being raised or lowered to the required height, and fixed at the required height by the set screw (E). A tin of petrol is then slid down the chute the lower corner of the front end of the tin striking against and being pierced by the steel cutter (G) allowing the petrol to flow down the chute through the strainer (K) into the tank of the car. To enable the petrol to flow 95 freer and faster out of the tin the striker (I) is pulled back against the tension of the spring (J) by the operator and then released. The tension of the spring (J) 100 throws the striker forward and the pin (M) pierces a vent hole in the tin.

105 When it is desired to clean the strainer (K) it is merely necessary to remove the

screws or other fastening means which secure the metal strip (F) to the chute (D) when the whole strip (F) may be removed and the strainer cleaned.

Having now particularly described the nature of the said invention and in what manner the same is to be performed, we declare that what we claim are:—

1. A liquid dispensing device including a funnel supported in fixed inclination, and a removable strip therein, a strainer at the

lower end of said strip, and a puncturing device carried by said strip above said strainer.

2. A liquid dispensing device as claimed in claim 1 in which the lower ends of the funnel and strip have tapered lower portions positioned one within the other.

Dated at Cape Town in the Union of South Africa this 25th day of February 1926.

THOMAS DAVID MANUEL.
